UNITED STATES PATENT OFFICE

RONALD W. CATTO, OF TORONTO, ONTARIO, CANADA

CONCEALED HEATING FOR BATHROOMS

Application filed November 5, 1930. Serial No. 493,541.

In modern homes, generally speaking, and in many apartment houses, the bathroom is very small in size, and this room is invariably heated by means of either a hot air duct opening thereinto, or else by means of radiators of various types. When radiators are used, they are either placed in a recess in a wall of the room, or else placed in some convenient part of the room. In this latter case, the radiator occupies space that should be available for use by the occupants of the house. In the other case, the countersinking, so to speak, of the radiator in the wall of a room, adds to the expense of constructing the wall. And in both cases the exposed radiator mars the appearance of the room.

Now one of the objects of my invention is to utilize what is at present practically waste space in a bathroom within which to locate the heating means for the room, and at the same time positively promote circulation of the heated air therein into the room, and in the following specification and the drawings forming part thereof, I shall disclose one form of my invention, and a modification thereof, and what I claim as new will be set forth in the claims forming part of this specification.

Fig. 1 is a cross section through one form of standard bathtub showing a radiator positioned in a chamber located at one side of the tub. Fig. 2 is a front elevation of portion of the wall used in conjunction with the bathtub to form a chamber for the radiator, the said wall being shown as suitably apertured to provide for circulation of the heated air through this chamber into the room. Fig. 3 is a view similar to Fig. 1 except that the type of bathtub disclosed therein is provided with an apron, portion of which has been removed. In the chamber formed at the side of this bathtub is located the outlet for the hot-air duct, and Fig. 4 is a view similar to Fig. 2, except that portion of the apron of the second-mentioned bathtub is shown in the drawings.

In the drawings, like characters of reference refer to the same parts.

Referring to the drawings, 2 is the bathtub, and the same is provided with a wall 3,

which terminates at its upper portion in a flange 4. This flange is substantially horizontal, and terminates in a downturned edge-flange 8. 5 is the wall placed in spaced relationship in respect of the wall 3, and the shape and construction of this wall may vary within a wide range, provided it is adapted to permit circulation of air therethrough into the said chamber, without departing from the spirit of my invention. I prefer to form this wall with a horizontal top flange 6 which extends inwardly in contact with the lower edge of the flange 8, and terminates in a vertical edge-flange 7 which rests underneath the flange 4 and in contact with the inner side of the flange 8. This construction lends itself for packing so as to prevent water getting between these parts. As shown clearly in Figs. 1 and 3, the spaced relationship of the wall 5 in respect of the wall 3 provides a chamber within which, having regard to Fig. 1, is placed the radiator 11, which may be of any suitable type. The air to be heated passes into this chamber through the apertures 12 and thereout of through the apertures 13. Thus it will be seen that positive circulation of the air through this chamber is provided for, and this circulation will positively promote the circulation of the air in the room.

Any suitable means may be employed to retain the wall 5 in position. For example, this wall may be provided with one or more bosses 10 through which may be tapped bars 9. These bars are adapted to rest in contact with the walls 3 and thus hold the top portions of the walls 5 in position. A suitable stop 14 may be fixed to the floor of the bathroom, in proper position, so as to prevent the bottom portion of the walls 5 being moved too far inward.

Referring to Fig. 3, 11' is the hot-air register, and this is located to open into the chamber between the walls 5 and 3.

The form of bath shown in Figs. 3 and 4 is partially provided with an apron 5'. I have made this illustration to show that the idea of my invention may be carried out with this style of bathtub.

Although I have shown the walls 5 as resting in contact with the floor, these walls may

be supported at their bottom portions in spaced relation to said floor, thus permitting me to omit the apertures 12 and yet provide for the circulation of the heated air through 5 the said chamber.

Since the space now occupied by the radiator is available for use by the occupant of the bathroom, by means of my invention, I have, in effect, increased the size of the room.

- 10 Another advantage flowing from my invention resides in the fact that since the heated air circulates through the chamber between the walls 5 and 3, it will pass into the room well removed from any of the walls thereof, 15 thus avoiding the marring of these walls.

Various changes in details of construction will suggest themselves to one skilled in the art, without in any manner departing from the spirit of my invention.

- 20 What I claim as my invention is:

1. The combination with a bath tub having an outwardly directed horizontal top flange terminating in a relatively short downturned edge flange spaced from the wall of the tub, of 25 a floor supported vertical wall associated with the upper edge flange of the tub and located in spaced relation to the wall of the tub to form a chamber for housing a floor supported radiator, said wall having grille areas 30 therein to promote the circulation of heated air through said chamber into a room, a horizontal flange at the upper edge of the vertical wall directed toward the wall of the tub, disposed beneath and engaged with the downturned edge flange of the tub and an upwardly 35 extending edge flange on the free edge of the wall flange disposed inwardly of and contacting the downturned edge flange of the tub to provide an interlocking connection 40 between the tub and wall.

2. The combination with a bath tub having an outwardly directed horizontal top flange terminating in a relatively short downturned edge flange spaced from the wall of the tub, 45 of a floor supported vertical wall associated with the upper edge flange of the tub and located in spaced relation to the wall of the tub to form a chamber for housing a floor supported radiator, said wall having grille 50 areas therein to promote circulation of heated air through said chamber into a room, and a flange at the upper edge of the vertical wall directed toward the wall of the tub with the free edge of the wall flange interlockingly 55 engaged with the inner side of the downturned edge flange on the tub wall.
